United States Patent Office

Des. 223,735
Patented May 30, 1972

223,735

SUTURE CUTTER

Albert E. Straus, Erie, Pa., assignor to
Perry Plastics, Inc., Erie, Pa.

Filed June 15, 1970, Ser. No. 23,467

Term of patent 14 years

Int. Cl. D24—03; D28—03

U.S. Cl. D83—12

FIG. 1

FIG. 2

FIG. 1 is an isometric view of the suture cutter according to the invention, taken from one side;

FIG. 2 is an isometric view of the suture cutter taken from the other side.

The bottom portion of the blade is conventionally plain.

I claim:

The ornamental design for a suture cutter, as shown and described.
